UNITED STATES PATENT OFFICE.

EDSON O. SESSIONS, OF CHICAGO, ILLINOIS.

LOCKING-SWITCH.

1,213,960.

Specification of Letters Patent. Patented Jan. 30, 1917.

Application filed June 14, 1915. Serial No. 33,926.

To all whom it may concern:

Be it known that I, EDSON O. SESSIONS, a citizen of the United States, residing at Chicago, in the county of Cook and State of Illinois, have invented certain new and useful Improvements in Locking-Switches, of which the following is a specification.

My invention relates to an improved form of locking switch adapted for use particularly in connection with high-tension circuits where it is desirable to install the switch in places not accessible to the operator without the use of some special tool or device for reaching the switch so that the switch and its associated parts may not be accidentally touched by the person of the operator, thus endangering his life and safety. Complicated devices have been proposed in the past for accomplishing the locking of switches of this kind in their closed position, and on account of the many parts involved in the locking mechanism these devices have not given unqualified satisfaction.

It is an object of the present invention to reduce the locking mechanism to the fewest number of parts possible, thus making the device positive, both in its locking and unlocking operations, and, furthermore, to secure a strength of construction amply adequate to meet all demands that may be made upon the locking device. This construction is, furthermore, characterized by locating the locking parts outside of the main path of the current flow so that little or no current flows through the lock itself, thus insuring the lock against the detrimental effect of heating and arcing.

The several drawings illustrating my invention are as follows:

Figure 1 shows a double-throw switch constructed in accordance with my invention; Fig. 2 shows in a vertical sectional view through the lock casing the lock mechanism employed in the form of switch shown in Fig. 1; Fig. 3 is a sectional view of the parts shown in Fig. 2 taken along the line 3—3; Fig. 4 is a sectional view of the parts shown in Fig. 2, taken along the line 4—4; Fig. 5 shows in view similar to Fig. 2 a form of locking mechanism for a single-throw switch; Fig. 6 is a sectional view of the parts shown in Fig. 5, taken along the line 6—6; Fig. 7 shows in a view similar to Fig. 5 a modified form

55 of locking mechanism for a single-throw

switch; Fig. 8 shows a portion of an operating device for operating the lock and switch; Fig. 9 shows in a view similar to Fig. 1 my locking mechanism as used in connection with high-tension fuses; Fig. 10 shows in a view similar to Fig. 7 a modified construction of lock in which a helical spring is employed instead of a flat spring; Fig. 11 shows in a view similar to Fig. 10 a modified construction in which the spring is differently applied; and Fig. 12 shows in a view similar to Fig. 2 a modified lock construction in which a helical spring is employed to hold the double latch in operative position.

Similar numerals refer to similar parts throughout the several views.

As shown in Figs. 1, 2, 3 and 4, the switch consists of a switch blade 10 pivotally mounted at 11 between connecting jaws 12 forming one terminal of a circuit. The switch jaws 13 and the switch jaws 14 are supported from the same insulating mounting plate 15 as the jaws 12, to be engaged by the switch blade 10 when in one or the other of its circuit-closing positions. It is immaterial to the present invention what the particular form of mounting of the switch blades may be and whether they have individual or common insulating devices for properly insulating them from surrounding objects, depending upon the voltage employed in the circuit controlled by the switch.

As shown in Figs. 2, 3 and 4, the switch blade 10 has secured by rivets or equivalent fastening devices 16 a housing 17 projecting from the end of the switch blade, which housing has pivotally supported therein upon a transverse rod 18 two latches 19 and 20, each being in the general form of a bell crank lever. These latches are of reduced thickness adjacent to the pivot rod 18, and their inner ends 19^a and 20^a where they do not come in contact with each other are of a width substantially equal to the distance between the opposite walls of the casing 17. A slot 21 is formed through each of these opposite walls of the casing 17 and beyond the normal position of the ends 19^a and 20^a of the latches to permit one or the other of the latches as desired to be engaged by any convenient operating tool, as, for example, that shown in Fig. 8, by inserting the bent metal end 22 carried by the insulating

rod 23 of the operating tool, as a result of which the lock and switch may be operated in a manner to be described.

The outwardly-extending end of each of the latches 19 and 20 has formed thereon a hook 19^b and 20^b for engaging a corresponding catch 24 or 25, according to whether the switch blade is in engagement with the contact jaws 13 or 14, respectively. The catch 24 is of substantially the same thickness as the switch blade 10, and is secured in the bottom of the groove between the contact jaws 13 by means of screws 26 which pass through elongated slots in the catch 24 so that the catch may be moved longitudinally between the contact jaws 13 to properly engage the latch 19. The catch 25 is similarly mounted between the contact jaws 14 and adjusted to engage the latch 20.

Both of the latches 19 and 20 are normally held in a position to engage the corresponding catches by a spring 27 bent near its middle portion to engage a rib 28 projecting inwardly from the wall of the casing so that displacement of the spring in the casing is prevented. The latches 19 and 20 are held in proper engaging position against the action of the spring 27 by offset portions 19^c and 20^c, which normally rest against the end of the switch blade 10. The engaging surfaces of the catches 24 and 25 and the hooks 19^b and 20^b are rounded, as indicated, to readily move the latches against the action of the spring 27 so that the hooks may clear the locking points of the catches when the switch blade is being moved to its closed position in either the contact jaws 13 or 14.

On account of the comparatively small amount of room afforded in the housing 17 by the thickness of the switch blade 10, and since it is desirable to mount both of the latches upon the same rod 18, I prefer to employ the construction indicated in Fig. 3 in order to afford a maximum bearing surface for each latch in connection with said pivot rod. In the construction shown, the latch 19 is provided with a comparatively thin hub 19^d projecting from its inner face around the pin 18, the amount of this projection being some distance past the center line of the housing, and the latch 20 is counterbored and provided with a tubular flange 20^d, which has a sliding fit with the outer cylindrical surface of the hub 19^d so that the latch 20 is supported upon the hub 19^d as well as upon the rod 18. In this way a considerable bearing surface is provided for each latch, and as the end portions of each latch are of practically the thickness of the space between the walls of the housing, there is practically no opportunity for displacement of either latch in the housing due to wear of the parts.

With the construction described, when

the switch blade 10 is in the position indicated in Figs. 1 and 2, the latch 19 engaging the catch 24 positively holds the switch blade between the jaws 13, thus insuring that the switch blade cannot be accidentally moved from engagement with said jaws. Furthermore, since the rod 18 is located substantially in line with the locking faces of the hooks 19^b and 20^b, it is impossible to disengage the latches from their catches by pulling on the switch blade or the outside of the housing 17. When it is desired to operate the lock so as to move the switch blade from the position shown in Figs. 1 and 2, the operating tool (which may have either the construction shown in Fig. 8, or any convenient construction) is inserted through the slot 21 in the housing and pulled downward. This pull first engages the end 19^a of the latch 19, moving the latch against the action of the spring 27 upon the pivot rod 18 to disengage the hook 19^b from the catch 24, and when this is accomplished the operating device engages the ends of the slots 21, and a continued pull on the operating device is communicated directly to the housing 17 and moves the switch blade from engagement with the contact jaws 13. If it is desired to leave the switch in its open position, the operating device may be removed when the switch blade is moved to a position substantially midway between the contact jaws 13 and 14. If, however, it is desired to close the switch in its reversed position, the motion of the switch blade 10 is continued by means of the operating device, and as the direction of motion is now upward against the latch 19, in moving the contact blade into engagement with the contact jaws 14 the latch 20 is free to engage the catch 25 under the action of the spring 27, after which the operating device is removed.

In the modified construction shown in Figs. 5 and 6 the switch is of the single-throw type, and for this construction the switch blade 10^a has secured to its free end the housing 17^a similar to the housing 17 described above, the principal difference being that there is mounted in this housing but a single latch 19^e for engaging the catch 24^a when the switch blade is in engagement with the contact jaws 13^a. In this construction the latch 19^e is of substantially the conformation described above for the latch 19, and this latch is pivotally supported upon a rod 18^a carried by the housing 17^a, so that the operation of the latch 19^e is substantially the same as described above for the latch 19. With this construction a spring 27^a is employed to hold the latch normally in its engaging position, and this spring is preferably secured to the casing by rivets, as indicated, or by some similar fastening means. The casing is pre-

vided through its opposite walls with slots 21^a for the reception of the operating tool 22, and a curved wall 29 is preferably made a part of the casing at the end of the slots 21^a opposite to the operating portion of the latch 19^c, which curved wall extends between the opposite sides of the casing so as to form a closure across the casing at the end of the slots referred to. This prevents the spring from getting out of place, and prevents the insertion of foreign matter into the casing and also gives the casing a better appearance than as though the said wall were not present. In this construction the catch 24^a is substantially the same as the catch 24, and is similarly mounted between the contact jaws.

In the modified construction shown in Fig. 7, the switch is of the single-throw type, and the switch blade 10^b has secured to its free end a casing 17^b similar to the casing 17^c. In this construction the latch 19^c is somewhat differently conformed, in that the pivot rod 18^b supporting said latch and extending between opposite walls of the casing 17^b is located a considerable distance from the center line of the casing and switch blade away from the hook portion 19^c of the latch. In this manner a maximum length of latch between the pivot rod 18^b and hook 19^c is secured, so that the necessary amount of motion of the hook may be had with a minimum amount of motion of the operating tool. This construction also permits of the catch 24^b being of less height, since the amount of metal between the switch blade and the hook may be reduced to merely that required for mechanical strength to positively hold the switch in its closed position, whereas with the construction shown in Figs. 2 and 5 a greater width is required to secure the same throw of the hook of the latch for a given amount of motion of the operating tool. With the exception noted, the catch 24^b is similar to the catches 24 and 24^a described above, and is similarly mounted between the contact jaws 13^b. With this construction a spring 27^b is employed to normally hold the latch 19^c in its engaging position, this spring being somewhat differently shaped than the spring shown in Fig. 5 to accommodate itself to the different conformation of latch, but in other respects the operation of the spring and its manner of support are substantially the same as for the spring 27^a shown in Fig. 5.

In the construction shown in Fig. 9, the jaws 33 and 34 are engaged by the end connectors 35 and 36 of a tubular fuse 37, the connector 35 being pivotally secured to the jaw 33 at 38, and the connector 36 being provided with locking mechanism contained in the casing 39 for holding the connector 36 in position in the jaw 34, which locking mechanism may either be of the

construction above described or that shown in Figs. 10 or 11, as desired.

In the drawings the construction of locking mechanism in the casing 39 is assumed to be that shown in Fig. 10. The jaws 33 and 34 are mounted upon supporting clamps 40 and 41, which, in turn, are supported by the outer ends of the high-tension insulators 42 and 43, these insulators being, in turn, secured in any suitable manner to a desired support. The operation of moving the fuse into or out of engagement with the jaw 34 and the accompanying operation of the locking mechanism is similar to that above described, and as far as this operation is concerned the structure is in effect a switch. In view of this, I desire to have it understood that where the term "switch blade" is used in the claims I mean either a simple switch blade as shown in Fig. 1, or any other similar construction in which the ends of a circuit-connecting member engage contact jaws with which it is desirable to positively hold the member in circuit-closing engagement.

As a result of the construction shown in Fig. 9, when it is necessary to replace the fuse 37 the fuse is moved from engagement with the contact jaw 34 in substantially the manner that the switch blade 10, above described is opened, and the new fuse may be inserted in the connecting terminals 35 and 36 by loosening the clamping screws indicated, after which the fuse and connector 36 may be moved so as to engage the contact jaw 34 and bring the parts of the locking mechanism into their engaging position.

As shown in Fig. 10, the locking mechanism consists of a latch 44 and catch 45 similar to the latch and catch shown in Fig. 7, the principal difference being that a helical spring 46 is connected at one end to the outer end of the operating member of the latch, while the other end of said spring is connected to a rod 47 extending between the side walls of the casing. As a result of this construction, when the latch is operated the spring 46 is lengthened, and, being a tension spring, it tends at all times to hold the latch in its locking position. While the flat spring above described gives very good results, among the advantages of helical springs arranged as described may be mentioned complete inaccessibility from the outside of the casing so that it is impossible to tamper with them, and greater uniformity of operation. A guard wall 48 extends completely around the opening 49 through the casing for the reception of the operating tool, except that portion of the opening through which the operating member must project to secure proper operation of the latch.

In the modified construction shown in Fig. 11, the locking mechanism is substantially the same, with the exception that the

spring 46^a is located between the opening 49^a and the pivot of the latch 44^a, instead of having the opening 49 between the latch 44 and the spring 46, as indicated in Fig. 10. In this construction the lower end of the spring is secured to the operating member of the latch and the upper end of the spring is secured to a rod 47^a extending between the side walls of the casing.

In the construction shown in Fig. 12, the latches 50 and 51 are similar to the latches 19 and 20 shown in Fig. 2, and are similarly supported upon a pivot rod 52 extending between the side walls of the casing 53. In this construction, however, the ends of the operating members of the latches are extended beyond the opening 54 for receiving the operating tool and at their ends are engaged by the ends of a helical spring 55, as a result of which the tension of the spring tends at all times to hold each latch in its locking position. The operation of the latches 50 and 51 is similar to that described in connection with Figs. 1 and 2 for the latches 19 and 20, and the advantages above referred to for the helical spring arrangement are secured by the construction shown in Fig. 12 over that shown and described in connection with the flat spring arrangement in Fig. 2. Guard walls 56 are provided along the sides of the opening 54 to prevent access to the interior of the casing 53 through said opening.

As a result of the construction described, it will be seen that I have provided a locking mechanism for switches of this kind in which the number of parts is reduced to a minimum, there being but two parts for each lock, to-wit, the latch and the spring associated therewith, and that for the double-throw switch there are but three parts, to-wit, the two latches and the common spring for holding the latches in their engaging position. Thus the operation of the lock is made direct and positive, and the construction is inexpensive to manufacture.

While I have described above a single switch blade as equipped with my improved locking devices, it will be understood that the locking mechanism is equally applicable to a double-pole switch construction, and that it is immaterial whether a single switch blade or a plurality of blades is employed.

By the term "contact jaw" as used in the claims, it will be understood that I mean any form of contact adapted to engage the switch blade for closing a circuit whether said contact comprises one or more slotted or unslotted plates or any other equivalent construction; and by the term "operating member" as used in the claims I mean the part of the latch, as for example the part 19^a, directly engaged by an external operating means, as for example the operating rod 22.

While I have shown my invention in the

particular embodiments above described, I do not, however, limit myself to these arrangements, as I may employ any equivalents thereof within the scope of the appended claims in carrying out my invention. 70

What I claim is:

1. In a switching mechanism, the combination of a pivoted switch blade having two operative positions, two contact jaws, one for engagement with said blade in each operative position, a catch associated with each jaw, a casing carried by the end of said blade, two latches pivotally mounted in said casing, one for engagement with each catch, each latch having an operating member rigidly associated therewith, and a helical spring secured at its ends to said operating members for holding said latches in position to engage said catches. 75

2. An electric switch comprising a pair of 85 posts, a switch blade pivotally connected to one of the posts, a catch lug adjacent the other post, switch jaws adjacent said catch lug, a bracket secured to the blade, and a hook pivotally connected to the bracket, said bracket being at such distance from the pivot of the blade as to cause the hook to co-act with the catch lug when the blade is closed, said bracket having an eye to be engaged by an operating implement, and the hook having 95 an ear overlapping said eye. 95

3. An electric switch comprising a pair of 100 posts, a switch blade pivotally connected to one of the posts, a catch lug adjacent the other post, switch jaws adjacent said catch lug, a bracket secured to the blade, and a hook pivotally connected to the bracket, said bracket being at such distance from the pivot of the blade as to cause the hook to co-act 105 with the catch lug when the blade is closed, said bracket having an opening for receiving an operating implement, and the hook having an ear overlapping said opening, and a spring tending to hold said hook in its engaging position and said ear in its overlapping position. 110

4. An electric switch comprising a pair of 115 posts, a switch blade pivotally connected to one of the posts, a catch lug adjacent the other post, switch jaws adjacent said catch lug, a bracket secured to the blade, and a hook pivotally connected to the bracket, said bracket being at such distance from the pivot of the blade as to cause the hook to co-act 120 with the catch lug when the blade is closed, said bracket comprising a casing for containing said hook and provided with openings through its opposite walls for receiving an operating implement, and said hook having an ear located between said 125 walls and overlapping said openings. 125

5. An electric switch comprising a pair 130 of posts, a switch blade pivotally connected to one of the posts, a catch lug adjacent the other post, switch jaws adjacent said catch

- lug, a bracket secured to the blade, and a hook pivotally connected to the bracket, said bracket being at such distance from the pivot of the blade as to cause the hook to co-act with the catch lug when the blade is closed, said bracket having an opening for receiving an operating implement, and said hook having an ear overlapping said opening, and devices for mounting said catch lug so that it may be moved longitudinally of said blade to different operative positions.
6. An electric switch comprising three posts located in substantially the same plane, a switch blade pivotally connected to one of said posts, a catch lug adjacent each of the other posts, switch jaws adjacent each of said catch lugs, a bracket secured to the blade, and two hooks pivotally connected to the bracket, said bracket being at such a distance from the pivot of the blade as to cause each hook to co-act with a catch lug when the blade is closed in either of its operative positions, said bracket having an opening for receiving an operating implement, and each hook having an ear overlapping said opening.
7. An electric switch comprising three posts located in substantially the same plane, a switch blade pivotally connected to one of said posts, a catch lug adjacent each of the other posts, switch jaws adjacent each of said catch lugs, a bracket secured to the blade, and two hooks pivotally connected to the bracket, said bracket being at such a distance from the pivot of the blade as to cause each hook to co-act with a catch lug when the blade is closed in either of its operative positions, said bracket having an opening for receiving an operating implement, and each hook having an ear overlapping said opening, and a spring tending to hold both hooks in position to co-act with said catch lugs.
8. An electric switch comprising three posts located in substantially the same plane, a switch blade pivotally connected to one of said posts, a catch lug adjacent each of the other posts, switch jaws adjacent each of said catch lugs, a bracket secured to the blade, and two hooks pivotally connected to the bracket, said bracket being at such a distance from the pivot of the blade as to cause each hook to co-act with a catch lug when the blade is closed in either of its operative positions, said bracket having an opening for receiving an operating implement, and each hook having an ear overlapping said opening, each hook having an ear overlapping said opening, each hook forming a part of the pivot bearing of the other hook.
9. An electric switch comprising three posts located in substantially the same plane, a switch blade pivotally connected to one of said posts, a catch lug adjacent each of the other posts, switch jaws adjacent each of said catch lugs, a bracket secured to the blade, and two hooks pivotally connected to the bracket, said bracket being at such a distance from the pivot of the blade as to cause each hook to co-act with a catch lug when the blade is closed in either of its operative positions, said bracket comprising a casing for containing said hooks and provided with openings through its opposite walls for receiving an operating implement, and each of said hooks having an ear located between said walls and overlapping said openings.
10. An electric switch comprising a pair of posts, a switch blade pivotally connected to one of the posts, a catch lug mounted adjacent the other post, switch jaws adjacent said catch lug, a bracket carried by the blade, and a hook pivotally connected to the bracket, said bracket being at such a distance from the pivot of the blade as to cause the hook to co-act with the catch lug when the blade is closed, said bracket having an opening for receiving an operating implement and the hook having an ear overlapping said opening.
11. An electric switch comprising three posts located in substantially the same plane, a switch blade pivotally connected to one of said posts, a catch lug adjacent each of the other posts, switch jaws adjacent each of said catch lugs, a bracket secured to the blade, and two hooks pivotally connected to the bracket, said bracket being at such a distance from the pivot of the blade as to cause each hook to co-act with a catch lug when the blade is closed in either of its operative positions, said bracket having an opening for receiving an operating implement, and each hook having an ear overlapping said opening, the pivots of said hooks being located in a common axis extending through the intersection of the center line of said blade and a line through the engaging surfaces of said hooks.

In witness whereof, I hereunto subscribe my name this 10th day of June, A. D. 1915.

EDSON O. SESSIONS.
